UNITED STATES PATENT OFFICE.

EMIL H. W. ULLRICH, OF NEW YORK, N. Y., ASSIGNOR TO WESTINGHOUSE ELECTRIC & MANUFACTURING COMPANY, A CORPORATION OF PENNSYLVANIA.

SWITCH MECHANISM.

Application filed August 3, 1921. Serial No. 488,430.

My invention relates to switch mechanism and particularly to switch mechanism of the safety enclosed type.

One object of my invention is to provide a switch mechanism wherein the switch and cover are so interlocked that the cover cannot be opened while the switch is in closed position and wherein the switch cannot be closed so long as the cover is in open position.

Another object of my invention is to provide a switch mechanism, having the above characteristics, wherein the interlocking mechanism is of simple, rugged and inexpensive construction that may be readily assembled.

Another object of my invention is to provide a switch mechanism wherein the operating lever for the switch is a unitary structure having a portion adapted to co-operate with the cover for interlocking the cover and switch.

A further object of my invention is to provide a latch mechanism for the cover that is adapted to receive the hasp of a lock for locking the latch in closed position.

These and other objects, that will be made apparent throughout the further description of the invention, are attained by means of the switch mechanism hereinafter described, and illustrated in the accompanying drawings, wherein:—

Figure 1 is a view, partly in section and partly in elevation, of a switch mechanism embodying features of my invention, the section being taken on the plane of the line I—I of Fig. 2;

Fig. 2 is a view, partly in section and partly in elevation, of the switch mechanism shown in Fig. 1, the section being taken on the plane of line II—II of Fig. 1;

Fig. 3 is a view, partly in section and partly in elevation, of a fragment of a modified form of switch-operating lever;

Fig. 4 is an elevational view of the mechanism shown in Fig. 3;

Fig. 5 is an elevational view of the switch mechanisms shown in Figs. 1 and 2;

Fig. 6 is an elevational view of a switch mechanism having a modified form of operating handle;

Fig. 7 is a view, partly in section and partly in elevation, of the switch mechanism shown in Fig. 6, the section being taken on the plane of line VII—VII of Fig. 6;

Fig. 8 is an elevational view of a switch mechanism showing a further modification;

Fig. 9 is a view similar to Fig. 3, showing a modified form of operating lever; and

Fig. 10 is an elevation of a fragment of a switch box showing a modified form of bearing structure for the switch-operating lever.

Referring to the drawings and particularly to Figs. 1, 2 and 5, the apparatus includes a box-like housing 11 made of sheet metal and having a cover 12 that is hinged to the side of the box by means of hinges 13. A switch panel 14 is secured to the bottom of the housing and supports a fuse member 15 and a switch member 16 which includes two sets of contact jaw members 17 and 18 which are of the usual construction employed in knife-type switches. Switch blade members 19 are pivoted to the jaw members 17 to engage the jaw members 18 when in closed position.

The switch-blade members 19 are mechanically connected by means of an insulating bar 21 and are actuated by an operating bar 22 which consists of a single piece of metal in the form of a round bar which is bent into an irregular shape for the purpose of providing a handle portion 23, bearing portions 24 which are journaled in openings 25 provided in the sides of the housing, and an interlock portion 26 which projects exteriorly of the housing and extends toward the cover and terminates in a curved or bent end portion 27.

The bar 22 is secured to the insulating bar 21 by means of an eye-bolt 28 that is yieldably attached to a clip 29 with which the bar 21 is provided. When the switch is in the closed position illustrated in full lines in Figs. 1, 2 and 5, the curved end 27 of the interlocking portion 26 is disposed adjacent to the cover, as shown, and serves to prevent opening movement of the cover by reason of the engagement thereof with the inwardly turned end 27 of the bar 22.

The cover 12 is provided with a circular opening or perforation 31 with which the end 27 of the bar 22 registers when the switch is in the open position, the position of the bar at such time being indicated by the broken lines in Figs. 1 and 5. The curvature of the bent end 27 is concentric with the axis of the hinges 13, and, consequently, the door may be opened only when the end

27 is moved into registry with the opening 31. It will be seen from the foregoing that the cover is held in closed position by the operating bar so long as the switch is in any position other than full-open position.

Inasmuch as the curved end 27 of the operating bar lies substantially contiguous to the side of the cover 12, the curved end 27 will project through the opening 31 when 10 the cover 12 is moved a slight distance toward open position. After the cover has been moved slightly toward open position, closing movement of the switch is prevented by reason of the engagement of the side wall 15 of the cover, having the opening 31, with the curved end 27 of the operating bar.

So long as the operating bar and the switch remain in the full-open position, the cover may be moved to the full-open position indicated by the broken lines in Fig. 2, where- 20 in it will be seen that it is not possible to actuate the switch toward closed position. The switch is held open until the cover 12 has been completely closed. At such time, 25 the curved end of the operating bar lies clear of the perforation in the cover.

By reason of the one-piece construction of the operating bar and interlock, and by reason of the fact that no additional parts are 30 required on the cover, the device may be manufactured inexpensively and is rugged and positive in its action.

Referring to Figs. 3, 4 and 9, wherein modified forms of operating bars are illus- 35 trated, the constructions therein shown include an operating bar 22 having a curvature concentric with the hinge axis from the point where the bar extends from the hous- 40 ing to the end thereof which is adapted to register with an opening 31 in the cover in a manner similar to the device previously described.

As shown in Fig. 9, the curved portion 27 comprises a piece of bent tubing which may 45 be fastened to the projecting end of the bar 22 after the bar has been assembled in the housing.

Referring to Figs. 6 and 7, a modified 50 form of operating bar is shown wherein the bar 22 is provided with an exteriorly ex- 55 tending interlocking portion 32 which, when the switch is in closed position, occupies the position indicated in full lines in Figs. 6 and 7, and which, when the switch is in open position, occupies the position indicated by 60 broken lines in the figures. It will be seen that, when the switch is closed, the extension 32 prevents opening movement of the cover and, when the switch is open, the extension 65 32 lies clear of the hinged edge of the cover side wall.

While the switch is in open position, the cover may be, therefore, moved to the open 70 position indicated in broken lines in Fig. 7. It will be seen, however, that, so long as

the cover remains in open position, closing movement of the switch is prevented by reason of the engagement of the extension 32 with the hinged edge of the cover.

Referring to Fig. 8, a modified form of 70 interlock is illustrated wherein the cover is provided with an angularly-disposed slot 33 with which the extension 32 registers when the switch is in open position. When the switch is in closed position, the extension 32 75 occupies the position indicated in full lines and prevents opening movement of the cover until the extension 32 is moved to open position wherein it is registered with the slot 33. When the switch is in open position, the 80 cover may be opened and, when the cover is open, closing movement of the switch is pre- 85 vented by reason of the engagement of the extension 32 with the wall 34 of the cover. It will be apparent that the interlock con- 85 structions above described are extremely simple and are inexpensive to manufacture.

In Fig. 10, I have shown a modified form 90 of bearing for the operating bar 22 which facilitates the assembly of the operating bar where the interlocking portions thereof interfere with the assembly of the bar within the bearings. The side wall of the housing is provided with a slot 35 which extends from the other edge thereof to the point at 95 which the bar is pivoted. A plate 36, having a bearing opening 37 through which the bar is inserted before assembly, is riveted or welded to the side of the box after the bar has been inserted in the slot. The plate 100 serves as a bearing for the bar and closes the slot.

While I have illustrated the interlocking mechanism as associated with a knife switch, it is apparent that the mechanism may be 105 effectively applied to various forms of switch mechanism, such as brush-type switches, ro- 110 tary switches or switches having quick-make- and-break attachments, and, in fact, to a switch of any type having a movable mem- 110 ber that may be actuated by an operating lever.

While I have described and illustrated several embodiments of my invention, it will be apparent to those skilled in the art that 115 other changes, modifications, substitutions, additions and omissions may be made in the apparatus illustrated without departing from the spirit and scope of the invention, as set forth in the appended claims.

I claim as my invention:—

1. Switch mechanism comprising a housing, a cover hinged to the housing, a switch and a switch-operating lever having a portion thereof projecting from the housing 125 and extending across the path of movement of the cover when the switch is closed for preventing opening movement of the cover so long as the switch is in closed position, a portion of said cover being cut away to re- 130

ceive the projecting portion of the operating lever when the switch is in its full-open position.

2. Switch mechanism comprising a housing, a cover hinged to the housing, a switch and a switch-operating lever having a portion thereof projecting from the housing and extending across the path of movement of the cover when the switch is closed for preventing opening movement of the cover so long as the switch is in closed position, a portion of the said cover being cut away to provide an opening registering with the projecting portion of said operating lever when the switch is in open position for permitting opening movement of the cover and for preventing closing movement of the switch so long as the cover is in open position.
3. Switch mechanism comprising a housing, a cover hinged to the housing, a switch and a switch-operating lever having a portion thereof projecting from the housing and extending across the path of movement of the cover when the switch is closed for preventing opening movement of the cover so long as the switch is in closed position, a portion of said cover being cut away to provide an opening registering with the projecting portion of the operating lever when the switch is in open position for permitting opening movement of the cover and for pre-

venting closing movement of the switch so long as the cover is in any other position than full-closed position.

4. Switch mechanism comprising a housing, a cover hinged to the housing, a switch and a switch-operating lever having a bent portion thereof projecting from the housing and extending across the path of movement of the cover when the switch is closed for preventing opening movement of the cover so long as the switch is in closed position, the said cover being provided with an opening with which the bent portion registers when the switch is in open position and into which the said portion projects when the cover is in open position, whereby closing movement of the switch is prevented so long as the cover is in open position.

5. Switch mechanism comprising a housing, a cover hinged to the housing, a switch and a switch-operating lever having a portion thereof projecting from the housing, the said cover being provided with an opening into which the said portion projects when the switch is in open position and the cover is open, whereby closing movement of the switch is prevented so long as the cover is in open position.

In testimony whereof, I have hereunto subscribed my name this 14th day of July, 1921.

EMIL H. W. ULLRICH.
